UNITED STATES PATENT OFFICE

160,370

TOY DISK GUN

Robert W. Clauss, Riverdale, N. Y.

Application January 6, 1949, Serial No. 80

Term of patent 3½ years

(Cl. D34—15)

To all whom it may concern:

Be it known that I, Robert W. Clauss, a citizen of the United States of America, residing at Riverdale, in the county of New York and State of New York, have invented a new, original, and ornamental Design for Toy Disk Gun, of which the following is a specification, reference being had to the accompanying drawing, forming part thereof.

Fig. 1 is a perspective view of the toy disk gun, showing my new design;
Fig. 2 is a side view;
Fig. 3 is a front view;
Fig. 4 is a rear view, and
Fig. 5 is a top view.

I claim:

The ornamental design for toy disk gun, substantially as shown.

ROBERT W. CLAUSS.
